UNITED STATES PATENT OFFICE.

WILLIAM P. OGDEN, OF DENVER, COLORADO.

CONCENTRATOR.

1,071,456.

Specification of Letters Patent. Patented Aug. 26, 1913.

Application filed October 7, 1910. Serial No. 585,862.

To all whom it may concern:

Be it known that I, WILLIAM P. OGDEN, a citizen of the United States, residing at Denver, in the county of Denver and State 5 of Colorado, have invented certain new and useful Improvements in Concentrators; and I do hereby declare the following to be a full, clear, and exact description of the invention, such as will enable others skilled in 10 the art to which it appertains to make and use the same.

My invention relates to improvements in means for taking metallic values from placer material or ground ores by concentration, my object being by improved construction and providing improved adjusting means, to permit the controlling and directing of the water and other materials in their movements upon or over the surface of the 20 concentrator.

A further object is to provide a concentrating table with means for adjusting such various portions of the same in such a manner as to tend to warp or twist the surface 25 thereof into any variations found desirable in the treatment of the various ores or placer material and to so construct such table as to permit of such twisting or warping without damage to the table and without 30 affecting the smoothness of the surface of the table.

A further object is to provide a concentrating table constructed in parts or sections which may be easily separated for 35 transportation or other purposes and easily joined together again.

A further object is to provide an apparatus which shall be of simple and economical construction and operation for the 40 accomplishment of the aforesaid objects.

With these and other objects in view my invention comprises certain novel features, constructions, combinations and arrangements of parts, hereinafter described, and 45 claimed, an embodiment of which is illustrated in the accompanying drawings, in which—

Figure 1 is a top plan view of the concentrator table, the method of mailing together the slats forming the same being indicated in dotted lines in a portion of said figure. Fig. 2 is a top plan view of the distributor. Fig. 3 is a plan view of the body portion of the table showing the general direction of the riffles. Fig. 4 is an end

view, showing detail of the adjusting mechanism with section showing detail of center supporting bracket and adjacent parts. Fig. 4^a is a vertical section through bracket 47 of Fig. 4. Fig. 5 shows in elevation the frame supporting the distributor. Fig. 6 shows one of the supports under the longitudinal center of the table. Fig. 7 is a vertical transverse section showing the arrangement of the slats composing the table proper, and the riffles above the slats, with a detail on a larger scale. Fig. 7^a shows a portion of the structure of Fig. 7, enlarged. Fig. 8 is a transverse section in detail showing means for holding the slats firmly in proper relations to each other. Fig. 9 is a view similar to Fig. 8 but showing a modification of the construction shown in that figure. Fig. 10 is a similar view showing a still further modification of the construction shown in Fig. 8. Fig. 11 is a similar view showing another modification of the construction shown in Fig. 8. Fig. 12 shows means for securing together the two longitudinal sections of the table. Fig. 13 shows detail of one of the brackets in which rest the heads of the bolts which support and adjust the table. Fig. 14 shows detail of one of the brackets forming part of the adjusting mechanism. Fig. 15 is a side elevation of the table and shows the supporting means and adjusting mechanism.

The same reference characters indicate the same parts in all views.

Referring to the drawings in detail, let 1 indicate the table proper, composed of slats 24 of wood, or other suitable material, secured together by nails 25 arranged in a suitable manner as, for instance, in the manner shown in Fig. 1. In cases where the table is to be transported by pack animals or there are other reasons making it desirable to separate the table into parts, the nails should be so arranged as not to cross some given longitudinal line of the table, preferably the center line as clearly shown at Fig. 1. In this way the table is divided, along said longitudinal line, into sections 2 and 3 which sections are normally secured together by suitable means as bolts 4 passing through slats 5 and 6 forming the inner edges of sections 2 and 3 respectively. The heads and nuts of these bolts are disposed in recesses 7 and 8 formed in the aforesaid slats 5 and 6 as clearly shown in Fig. 12. 105 110

The bolts may of course pass through more than one slat of each section if found desirable for giving more strength, though the bolts should not be so long as to interfere with the elasticity or flexibility of the table.

A modification of the construction of the table proper is shown in Fig. 8, in which longitudinal wires 26 are placed between the respective slats and form, in a measure, a tongue and groove connection so that when the slats are brought into intimate contact by the nails or other securing devices, no vertical displacement is permitted to result from the warping or twisting of the table hereinafter described. In Fig. 10 angular strips 26' are shown in place of the round wires 26, the purpose being the same. A further modification of this construction is shown in Fig. 9 in which two longitudinally arranged wires or strips are located between the respective slats, these wires being indicated by the numerals 27 and 28; the nails 25 in this case passing between the wires. The slats are not, however, brought into intimate contact, the wires or strips being only partly embedded, thus leaving a slight space 29 which will permit of sidewise expansion of the wood when saturated with moisture. In some cases, if no sidewise expansion be allowed for in a suitable manner as here shown, the expansion will all be upward resulting in distorting the surface of the table. Fig. 11 shows a still further modification in which the slats are formed with a double tongue 27' and 28' and a double groove 27" and 28", which hold the slats firmly in relation to each other but still allow for side expansion the same as the construction shown in Fig. 9.

At one end of the table any suitable distributing device as 9 is located, being supported by means of a frame work shown in Fig. 5 and consisting of uprights 10 and 11 connected near the bottom by a cross piece 12 and at the top by another cross piece 13. A diagonal brace 14 is located as shown and is provided at its upper end with a slot 15 through which a bolt 16 is arranged to pass; uprights 10 and 11 being also slotted as shown for the purpose of effecting a proper adjustment. The distributor 9 is formed with sides 17 and 18 and with a pivoted partition member 19 swinging upon a pivot 20 and providing means for regulating the spread of the stream of water flowing onto the table from the passageway 21 in relation to that of the pulp flowing onto the table from channel 22. A screen 23 located as shown serves the usual purpose.

The table proper is supported on a frame work consisting of end members 30 and 31 connected by longitudinal side bars 32 and braced diagonal pieces 33. The end members 30 and 31 include respectively cross-bars 34 and 35 to which are secured the ad-

justing devices for varying the inclination of portions of the table.

The table proper is provided with the side members 36 and 37 to which are attached brackets 38 shown in detail in Fig. 14. These brackets consist of base portions with two ears 39 and 40 projecting therefrom and provided with a smooth bore 41 for the accommodation of bolts 42 threaded at their upper portions and provided with angular portions 43 at their extreme ends in order that such bolts may be turned by the use of a key or wrench. Nuts 44, so set between the ears and against the base of the brackets as to prevent turning, engage the threaded portions of the bolts and the heads of such bolts are held in position by means of angular brackets 45 secured to cross-bars 34 and 35 respectively. The bore 41 in the ears 39 and 40 is larger than bolts 42 in order to allow for the play of the bolts. The table is pivotally mounted along its central longitudinal axis by means of brackets 47 secured to cross pieces 48 as by bolts 48^a indicated in Fig. 6 and extending downward into slots 49 formed in cross pieces 34 and 35 and secured to said cross pieces by bolts 50 as also shown in Fig. 6. The lower portion of end section 31 is a framework composed of uprights 54, braces 51 and cross pieces 52 and 52^a and 53 all solidly joined together in suitable manner as indicated. Guide members 54^a are solidly joined to cross piece 35 and extend downward between cross pieces 52 and 52^a and just within uprights 54. Cross pieces 52 and 52^a and uprights 54 thus form a slot in which the framework formed by cross piece 35 and guide members 54^a may be raised or lowered to the desired point. The raising and lowering is accomplished by threaded bolts 55 passing through brackets 56 and 57 mounted as shown. As the table proper is attached to cross piece 35 by the adjusting mechanism and by central brackets 47, the raising and lowering of cross piece 35 raises and lowers the foot of the table and thus the longitudinal slant of the table is adjusted.

The riffles 60 are arranged at substantially the angle shown in Fig. 3 and the table is so adjusted that the side 36 is higher than the side 37 and there is also a longitudinal inclination at a suitable angle as shown for example in Fig. 15. Along the upper side 36 is a channel 58 for receiving the concentrates which accumulate between the riffles and pass forward between the riffles to such channel and are thence discharged. The gangue, of course, discharges from the lower end of the table and the concentrates are drawn off through openings 59.

The central brackets 47 are made approximately Y shaped, as shown in Fig. 4^a, having a stem 47^a with a hole 47^b therein 130

through which bolt 50 passes. The cross piece 48 rests in the opening of the Y the bottom of which is flattened and made on an inclination similar to the longitudinal inclination of the table proper. Bolts 48^a 5 pass through the arms of the Y and through cross piece 48 and hold the same therein. These bolts fit loosely enough in cross piece 48 so that said cross piece is permitted to 10 slide upon the bolts. The stem 47^a extends down into slot 49 and is mounted therein on bolt 50. The slot 49 is slightly wider than the thickness of stem 47^a in order to allow for play of the stem when the longitudinal 15 inclination of the table is changed and for similar reasons hole 47^b has its edges well rounded as shown so as to allow play upon the bolt 50. The arms of the Y in the bracket at the lower end of the table are 20 spaced apart wider than the width of cross piece 48 so as to allow play of said cross piece in the Y when the lower end of the table proper is raised or lowered. This is 25 shown at Fig. 4^a.

By means of a key or wrench applied to 25 the top of bolts 42 the same may be turned in either direction. As the bolt is turned the nut 44, being threaded thereon and so set as to prevent turning, moves up or down 30 on the bolt, according to the direction in which the bolt is turned. As the nut is fixed between the ears of the bracket and the bracket is attached to the table, that portion 35 of the table adjacent the bracket must rise or lower with the nut. It is apparent that any portion of the table proper to which such adjusting means are attached may be raised or lowered, in relation to any other portion, as desired. It will be also apparent that 40 as many of the frameworks and adjusting mechanisms, shown in Fig. 4, as may be desired could be set at desired points along the table but in practice it is found that the construction shown, composed of the four 45 adjusting mechanisms, one at each side at each end of the table, will answer all ordinary requirements. The table being normally pivoted at the center as shown at Fig. 4, the longitudinal center line is normally 50 nearly stationary, having only the variation resulting from the tipping of the table on the axis, bolt 50, which is some distance below the longitudinal center line of the surface of the table.

It will be apparent that with the mechanism described the table may be kept in a plane if desired and given any desired longitudinal or transverse inclination, the longitudinal inclination being controlled by the 55 adjusting bolts 55 as already described and the transverse inclination being controlled by raising the nuts 44 on one side of the table and lowering those on the other side. It will also be apparent that either one or 60 more or all of the corners (in the construc-

tion shown) may be forced down or up in relation to the center line, each being operated independently of the others so that the surface of the table may be warped or twisted into almost any shape desired. 70 Even the bolt 50 may be removed from the bracket 47 to allow such twisting or warping as would tend to raise or lower the bracket beyond a point allowed by the bolt when in place. The twisting action given 75 to the floor of the table will cause the ripples formed in the covering thereof to warp slightly giving a wave like effect, although this effect need not be and generally is not regular in character. It is obvious that the 80 effect described will be manifested both in the bottom of the grooves and the side walls thereof. It will be understood that slats 24 and nails 25 are of such size, shape and material as to allow such warping as may be 85 found necessary but it will also be borne in mind that very slight variations of inclination, warping, etc., will be sufficient to completely change the action of such a thin sheet of water and such fine materials as 90 are ordinarily moving upon the surface of a concentrating table so that the table can be made in a very substantial manner and still, by the improved construction herein described, allow plenty of elasticity or flexibility for the desired warping or twisting 95 without damage to the table.

The combinations of metals and minerals in the ores and placer material to be treated by concentration methods are so varied and 100 there are frequently so many different metals of different specific gravities to be concentrated out of the same ore or placer material that it is ordinarily impossible to ascertain in advance just what kind or shape 105 of concentrating surface would be the most effective in the treatment of a given ore or placer material. Control, to a considerable extent, of the velocity and direction of movement of the water and other materials upon 110 the surface of the table, is required to accomplish the concentration of even a single metal of a given specific gravity and to concentrate, at different points upon the same table, different metals of sometimes only 115 slightly different specific gravities, will clearly require a very exact adjustment of the table and as the requirements of each case vary widely, it would be impracticable to construct a table with any given surface 120 to meet the requirements of any given case. To meet these difficulties, my invention enables the operator to so adjust the surface as to be not only most effective in the concentration of a single metal but also to so 125 vary the adjustment at different points on the surface that a variety of metals of different specific gravities may be concentrated and run off into the trough 58 at successive points of the table, each portion of the 130

table being adjusted to meet the requirements of the concentration desired on that portion.

In the use of my elastic or flexible construction and adjusting mechanism, as herein set forth, I do not wish to be limited to tables of any specific type as it is apparent that the same may be applied to a great variety of types of tables to advantage. It will also be apparent that many details of construction herein shown and described may be varied without in any manner departing from the spirit of my invention.

It will be understood that the riffles 60 may be formed in any approved manner and of any approved material of suitable flexibility but preferably by covering the slats with rubber having corrugations of the kind as shown at Fig. 7, the corrugations 20 constituting the riffles.

What I claim is:

1. In a concentrator, a supporting table formed of flexible slats, means for producing an irregular surface by mechanically warping portions of the table independently of other portions by twisting some of the slats around their longitudinal axes and a layer of material provided with a concentrating surface and yieldable to conform to the warping of the slats, said warping extending along the slats and toward the ends of the table.

2. In a concentrator, a supporting table formed of detachable sections, each section 35 comprising slats of flexible material, means for producing transverse strain on certain of the slats and twisting them around their longitudinal axes, thereby mechanically warping portions of the table and a layer of 40 material provided with a concentrating surface and yieldable to conform to the warping of the slats, said warping extending along the slats and toward the ends of the table.

45 3. In a concentrator, a supporting table formed of slats of flexible material, means for supporting the table approximately along its central longitudinal axis, means for twisting certain of the slats around their 50 longitudinal axes and thereby mechanically warping portions of the table between its central axis and the outer edges, and a layer

of material provided with a concentrating surface and yieldable to conform to the warping of the slats, said warping extending 55 along the slats and toward the ends of the table.

4. In a concentrator, a supporting table inclined transversely and formed of slats of flexible material, means for supporting the 60 table approximately along its central longitudinal axis, means for warping the table by twisting transversely the slats forming portions of the table, between such axis and the outer edges, without disturbing the elevation of other portions of the table and a layer of material provided with a concentrating 65 surface and yieldable to conform to the warping of the slats, said warping extending along the slats and toward the ends 70 of the table.

5. In a concentrator, a supporting table inclined transversely and longitudinally and formed of slats of flexible material, means for supporting the table approximately 75 along its central longitudinal axis, means for warping the table by twisting around their main axes, by transverse strain, the slats of portions of the table between said supporting means and the outer edges of the 80 table, without disturbing the elevation of other portions of the table and a layer of material provided with a concentrating surface and yieldable to conform to the warping 85 of the slats, said warping extending along the slats and toward the ends of the table.

6. In a concentrator, a table inclined in two directions and formed of flexible slats, means for producing an irregular surface by 90 mechanically warping portions of the table by twisting some of the slats around their longitudinal axes, and a layer of material provided with a concentrating surface and yieldable to conform to the warping of the 95 slats, said warping extending along the slats and toward the ends of the table.

In testimony whereof I affix my signature in presence of two witnesses.

WILLIAM P. OGDEN.
